UNITED STATES PATENT OFFICE.

CHARLES R. MOSS, OF RICHMOND, VIRGINIA.

DUST-PAN.

1,240,241.

Specification of Letters Patent. Patented Sept. 18, 1917.

Application filed July 12, 1916. Serial No. 108,904.

To all whom it may concern:

Be it known that I, CHARLES R. Moss, a citizen of the United States, residing at Richmond, in the county of Henrico and State of Virginia, have invented certain new and useful Improvements in Dust-Pans, of which the following is a specification, reference being had to the accompanying drawings.

10 This invention relates to certain improvements in dust pans and it is an object of the invention to provide a novel and improved device of this general character which may be effectively employed with convenience and facility without the necessity of the individual bending over and whereby the user is not compelled to engage the device with a hand in order to move the pan from one locality to another.

20 It is also an object of the invention to provide a novel and improved dust pan comprising a dust or dirt holding receptacle together with a hinged lid, said lid serving as a scoop or apron to facilitate the collection 25 of the dust or dirt within the receptacle.

The invention has for a still further object to provide a novel and improved dust pan including a hinged apron or scoop provided with means whereby the same may be readily 30 adjusted into an operative or inoperative position, relative to the surface to be cleansed, by the foot of the user.

Furthermore it is an object of the invention to provide a dust pan with novel and improved means whereby the same may be readily moved from one location to another through the medium of a sweeping implement such as a broom or brush.

The invention also has for an object to 40 provide a novel and improved dust pan comprising a receptacle into which the dirt or the like is adapted to be collected together with novel and improved means whereby the contents of the receptacle may be discharged 45 therefrom when desired.

The invention consists in the details of construction and in the combination and arrangement of the several parts of my improved dust pan whereby certain important 50 advantages are attained and the device is rendered simpler, less expensive and otherwise more convenient and advantageous for

use, all as will be hereinafter more fully set forth.

The novel features of the invention will 55 hereinafter be definitely claimed.

In order that my invention may be the better understood, I will now proceed to describe the same with reference to the accompanying drawings, wherein—

60 Figure 1 is a view in perspective of my improved dust pan showing a conventional straw broom operatively engaged therewith;

Fig. 2 is a transverse vertical sectional view taken through my improved dust pan, 65 a second position of the hinged cover being indicated by dotted lines;

Fig. 3 is a sectional view taken substantially on the line 3—3 of Fig. 2; and

Fig. 4 is a view in perspective illustrating 70 a dust pan constructed in accordance with an embodiment of my invention and having in operative engagement therewith a handle brush.

As disclosed in the accompanying drawings, 75 1 denotes the bottom or base of my improved pan having one end portion cut out, as at 2, to afford a discharge opening. The forward longitudinal margin of the bottom is returned to an upwardly inclined flange, 80 80 as indicated at 3, while the rear longitudinal margin is provided with the upstanding back wall 4 substantially perpendicular to the bottom or base 1 and having its upper longitudinal margin bent inwardly to afford 85 a flange 5, said flange 5 being on substantially the same incline as the flange 3 and in alignment therewith. The ends of the bottom or base 1 are provided with the upstanding end plates 6 which extend a predetermined distance above the flanges 3 and 5 90 for a purpose which is believed to be self-evident.

Hinged to the inner longitudinal marginal portion of the flange 3 is the apron or 95 scoop 7 which is adapted to close the space between the flanges 3 and 5 as is illustrated in full lines in the accompanying drawings, whereby the pan when being transported is arranged substantially dust-proof. When the 100 scoop or apron 7 is in the position indicated by dotted lines in Fig. 2, it will be perceived that the dirt or sweepings may be readily conveyed within the pan.

8 denotes a slide adapted to close the opening 2 and is moved longitudinally of the bottom or base 1 through the medium of the operating member 9 herein disclosed as a length of wire extending exteriorly of the pan through one end thereof and having its exterior portion formed into a finger hold, as indicated at 10. The member 9 is positioned along the back of the pan and is secured to the inner longitudinal marginal portion of the slide 8 as indicated at 11, said connection being preferably formed by inwardly rolling said marginal portion of the slide 8 to afford a barrel.

15 The forward or outer longitudinal marginal portion of the slide 8 is returned to afford a flange 12 underlying the flange 3 and contacting therewith whereby it will be perceived that said flange 12 coacts with the
20 flange 3 for maintaining the slide 8 firmly seated upon the bottom or base 1. This action is further facilitated by the inherent resiliency possessed by the flange 12.

The operating member 9 is extended upwardly as at 14, and terminates in the straight portion 15 which underlies the flange 5 at its outer or connected end, and it will at once be self-evident that the extended portions 14 and 15 serve an effective medium for maintaining the inner side of the slide 8 in proper contact with the base or bottom 1.

Extending longitudinally from an end of the scoop or apron 7 is a finger 16 terminating in a loop 17 which is adapted to be engaged by the foot of a person in order to throw the apron or scoop 7 into the position indicated by dotted lines in Fig. 2 or to return the same in a closed position as indicated by full lines in the accompanying drawings. The adjacent end plate 6 is provided with the open-end slot 18 to receive said finger 16 as is believed to be clearly illustrated in Figs. 1 and 4 of the drawings.

45 19-19 denote upstanding arms operationally engaged with the back wall 4 in predetermined longitudinally spaced relation and terminating a predetermined distance above the pan, and the upper end portions 20 of
50 said arms 19 are bent on a predetermined curvature to overlie the top of the pan and it is to be further observed that the portions 20 are disposed in converging planes as is particularly illustrated in Fig. 3. The upper or free extremities of the arms 19 or more particularly the curved portions 20 thereof are formed into the eyes or loops 21 for a purpose which is believed to be self-evident.

60 Fig. 1 illustrates a straw broom B of a conventional type in operative engagement with the pan, and it is for this reason that the portions 20 of the arms 19 are arranged in converging planes so that the same may 65 have effective engagement with the head of

the broom. When it is desired to change the location of the pan when in use, it is only necessary for the user to engage the head of the broom with the portions 20 of the arms 19 and thus lift the pan from one place to another. By this arrangement it will be perceived that it is unnecessary for the individual to stoop over to directly take hold of the pan. This is also true when a handle brush is employed as indicated at H in Fig. 4. However, when the handle brush H is used the convergence of the portions 20 is not necessary.

The arms 19 may be secured to the back wall 4 in any desired manner but as is particularly illustrated in Fig. 3, it will be noted that the arms 19 are formed from a single length of material, preferably wire, which is suitably threaded through the back wall 4 with the intermediate portion 22 thereof overlying the inner face of said back wall and disposed longitudinally thereof. Additional securing members 23 may be disclosed through the back wall 4 and co-acting with the arms 19 in order to impart additional rigidity thereto. 80 85 90

From the foregoing description, it is thought to be obvious that a dust pan constructed in accordance with my invention is of an extremely simple and comparatively inexpensive nature and is particularly well adapted for use by reason of the convenience and facility with which it may be assembled, and it will also be obvious that my invention is susceptible of some change and modification without material departure from the principles and spirit thereof and for this reason I do not wish to be understood as limiting myself to the precise arrangement and formation of the several parts herein shown in carrying out my invention, in practice, except as hereinafter claimed.

I claim:

1. A dust pan comprising a body having a portion of its top open, an apron hinged to the forward margin of the pan and serving as a closure for the open portion of the top, a portion of the bottom of the pan being open, a slide for closing said open portion, and an operating member for the slide extending exteriorly of the pan through an end thereof. 110 115

2. A dust pan comprising a body having a portion of its top open, an apron hinged to the forward margin of the pan and serving as a closure for the open portion of the top, a portion of the bottom of the pan being open, a slide for closing said open portion, and an operating member for the slide extending exteriorly of the pan through an end thereof, said operating member having its inner end portion extended and coacting with the top of the pan for holding the slide in contact with the bottom of the pan. 120 125

3. In combination with a dust pan includ- 130

ing a base and an upstanding back wall at right angles to the base, arms secured to the back wall and extending thereabove, said arms being spaced apart longitudinally of the back wall and also substantially perpendicularly related to the base of the dust pan, the outer extremities of the arms being angularly disposed and overlying the base of the

dust pan, the portion of the arms above the pan being free from each other at all points. 10

In testimony whereof I hereunto affix my signature in the presence of two witnesses.

CHARLES R. MOSS.
